UNITED STATES PATENT OFFICE.

PATRICK J. DUNN, OF HOLLAND, OHIO.

INSULATED RAILROAD TIE AND RAIL-FASTENING MEANS THEREFOR.

1,407,195.

Specification of Letters Patent. Patented Feb. 21, 1922.

Application filed June 4, 1921. Serial No. 474,968.

To all whom it may concern:

Be it known that I, PATRICK J. DUNN, a citizen of the United States, residing at Holland, in the county of Lucas and State of Ohio, have invented certain new and useful Improvements in Insulated Railroad Ties and Rail-Fastening Means Therefor, of which the following is a specification, reference being had to the accompanying drawings.

It is well known that the life of wooden cross ties is relatively short, hence necessitating the general repair of railroads, as well as the renewal of ties now and then, as some ties decay sooner than others. Therefore the purpose of the present invention is to provide an improved glass tie, suitably reinforced, and including shock absorbers for the rails and rail fastening devices, thereby prolonging the life of railroads, and lessening the repairs to the road.

Another purpose consists in the provision of a glass tie for railroads, acting as insulation for the rails, and not only to provide a practical tie of this character, but also providing a construction particularly adapted for use in connection with electrical signaling systems.

Still another purpose is the provision of a tie of this general character, which can be easily replaced when repairs are necessary, there being shock absorbers engaged in the upper surface of the tie, so as to cushion the rails, in order to avoid what is known as chattering of the rails. For instance it is known that a railroad built of ties that are too rigid, particularly at stations, the rails chatter in a short while, thereby rendering traveling very uncomfortable and annoying to the patrons of the road, hence the provision of the shock absorbers.

A further purpose is to provide depressions on the glass tie for the reception of the shock absorbers, which are designed to be constructed of wood treated with creosote or some other suitable material for the preservation of the wood, and also in order that the wood may act as a better shock absorber than any other material, though it is obvious that any other suitable fibre may be used.

Additionally, the invention aims to provide a tie including wire fabric reinforcing extending through the glass tie, in combination with suitable passages formed

through the tie, for the reception of rail fastening members, and keys for holding the members anchored in the tie, for the purpose of holding the rails in position. 60

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features 70 and combination of parts, as will be herein-after set forth, shown in the drawings and claimed.

In the drawings:

Figure 1 is a view in perspective of the 75 improved glass tie constructed in accordance with the invention.

Figure 2 is a longitudinal sectional view on line 2—2 of Figure 1.

Figure 3 is a cross sectional view on line 80 3—3 of Figure 2.

Figure 4 is a horizontal sectional plan view of the tie on line 4—4 of Figure 1, showing in dotted lines the form of the lower part of the openings, which receive 85 the anchoring members for the rail fasteners.

Figure 5 is a longitudinal sectional view through a suitable mold, showing the glass tie molded therein, with the proper wire 90 fabric reinforcing.

Figure 6 is a cross sectional view on line 6—6 of Figure 5.

Figure 7 is a detail view of one of the anchoring rods 11. 95

Figure 8 is a detail view of one of the wedge keys 20.

Figure 9 is a detail view of one of the rail retaining plates 14.

Referring to the drawings, 1 designates 100 the body of the improved glass tie, which may be any suitable length, width or thickness, and molded transversely of the tie is a plurality of tubes or sleeves, which are particularly employed for reinforcing the tie. 105 These sleeves or tubes 2 extend horizontally, and are located so as not to contact with the wire fabric reinforcing 3, which is embedded in the tie at the time of its construction. The wire fabric reinforcing extends the full length of the tie, and is arranged in horizontal planes, there being a 110

plurality of sections, so as to not only reinforce the tie generally, but also to withstand the strain centrally on the tie. It is to be noted that these sections of wire fabric reinforcing are located mostly near the lower portion of the tie, where the tie must withstand or resist the greatest strain.

In constructing the tie the upper surface thereof is provided with suitable depressions 4, which have their opposite side walls 5 V-shaped, for the reception of the shock absorbing blocks 6, which are preferably constructed of wood, though it is obvious that any other suitable material may be used. These shock absorbing blocks are thoroughly treated with creosote or any other suitable material, which will act to insure the preservation of the blocks. The shock absorbing blocks are shaped correspondingly to the depressions, so that when they are dropped into place in the depressions, the end V-shaped walls of the depressions will act to prevent movement of the blocks, not only laterally of the rails, but also in the direction of the rails. Obviously the weight of the rails retains the blocks in place.

At diagonally opposite positions relatively to the depressions 4, the tie is provided with openings or passages 7 extending vertically through the tie. These passages or openings 7 are in pairs, one pair adjacent each end of the tie, and it will be noted that the passages or openings of each pair are diagonally opposite each other. The upper and lower ends of the passages or openings are open, and the lower portions of the openings or passages have semi-circular undercut portions 8, the walls 9 of which constitute shoulders, to be engaged by offset lugs 10 on the lower ends of anchoring rods 11, which are designed for holding rail fastening plates in position. The openings or passages are similar in cross sectional shape to key holes. One portion of each passage or opening is substantially cylindrical, while the other part is rectangular, as will be seen in the horizontal sectional plan view.

The rail fastener retaining rods may be any suitable length according to the height of the tie, and each comprises an elongated shank 12, with a rectangular head 13 on its upper end, to be engaged by a wrench (not shown). In fact the wrench may engage the head, so as to turn the anchoring member a half turn, so as to cause the lug 10 of the anchor to engage the shoulder 9. The upper ends of the shanks of the anchoring members pass through rail retaining plates 14. These plates have bent portions 15 upwardly offset to overlie the opposite sides of the base 16. Nuts 17 are threaded upon the upper ends of the shanks of the anchoring members in order to hold the plates 14 in position. The anchors are first lowered or passed through the openings or passages, the cylind-

rical portions of the shanks being passed downwardly through the cylindrical parts of the openings or passages, with the lugs 10 passing through the rectangular portions. After the anchoring members are thus positioned, a wrench (not shown) is applied to the rectangular heads 13, whereupon the anchors are given a half turn, which will cause the lugs 10 to assume positions under the shoulders 9. The anchoring members will remain in place, and hold the plates 14 in such wise that their bent portions 15 will overlie the bases of the rails. Suitable cotter pins 18 engage through the upper extremities of the shanks, immediately above the nuts 17, thereby preventing accidental removal of the nuts. The shanks of the anchoring members at points immediately below the plates 14 are provided with elongated grooves 19, which receive the wedge keys 20. The wedge keys may be made of any suitable material, such as metal, and are shaped in order to conform to the rectangular portions of the passages or openings 7. The wedge keys 20 have one edge vertically disposed, while the other is inclined as shown at 21, to correspond and conform to the inclined walls 22 of the rectangular vertical portions of the openings or passages 7. The upper end edges of the wedge keys have enlargements 23, the ends of which act as handles for the mechanic, in applying the keys to the passages or openings. The enlargements 23 with their undercut edges, enable the workman or mechanic to easily extract the wedge keys. The vertical edges of the wedge keys engage said grooves 19 of the shanks of the anchoring members, acting to force them in place, and also acting to prevent rotary movement of the anchors.

As previously stated most of the wire fabric reinforcing is located near the bottom of the tie, in order to withstand the greatest amount of stress. More than one opening is provided for the reception of the cotter keys 18, in order to permit the taking up of slack or looseness of play between the several parts. The purpose for allowing the openings or passages 7 to be formed through the entire tie, is to permit any moisture whatever to drain off very quickly.

The tie is designed to be corrugated on its side and bottom faces, so as to more or less reinforce the tie.

The lower parts of the openings or passages 7 formed in the tie have their lower ends smaller than the lower ends of the anchoring members, thereby preventing the anchoring members from dropping through, when they are inserted in place. The anchoring members are also prevented from dropping through, owing to the cylindrical portions of the openings or passages 7 being out of alignment with the lower ends of said passages or openings.

As previously stated the tubes or sleeves 2 are incased or embedded in the tie between the opposed walls of the sheet metal reinforcing trough 40, and passing through the tubes or sleeves 2 are rods, stays or reinforcing bolts 41, which also pass through the opposite walls of the sheet metal reinforcing trough. The ends of these rods or stay bolts are swaged in order to provide 10 heads 42, in order to reinforce the sides of the sheet metal reinforcing. The opposite sides of the sheet metal reinforcing are also provided with a plurality of openings or perforations 43, through which the molten material as it is poured in the mold is allowed to flow, so as to completely incase or embed the sheet metal reinforcing in position. The sheet metal reinforcing may be supported in the mold in any suitable manner (not shown).

In order to construct the tie as made of glass suitably reinforced with wire fabric, and provided with the vertical passages or openings 7, it is the aim to provide a suitable mold, such as shown in Figure 5, comprising a sheet metal wall 26 forming the sides and bottom portions of the mold. Sheet metal end pieces 27 connect the side pieces for the ends of the mold. A suitable sheet metal top 28 engages upon the top edges of the sides and ends of the mold, there being suitable ears 29 for the reception of threaded extensions 30 of the end pieces 27, to retain the top in place. The top 28 of the mold is provided with cores 32, which form the openings or passages 7. In fact the cores conform to the passages or openings 7, and connected to the lower ends of the cores 32, by means of a tongue and 40 groove joint 31 are lateral extensions 31^a, which form the undercut portions, and also the shoulders 9. Obviously when the mold is taken apart, the top 28 is first removed, and since the cores 32 are carried by the top, they are likewise withdrawn from the glass forming the tie. When these cores are withdrawn, they automatically become detached from the extensions 31^a, which may then be removed from the openings or 50 passages, by turning them lengthwise. Unless extensions of the cores 32 are made in several or a plurality of parts, in this manner, there will be no way of forming the lower parts of the openings or passages 7, owing 55 to the formation of the shoulders. In fact the extensions 31^a are to be made of as many parts as will permit the removal of said extensions. In other words there will be no way of lifting the top of the mold, should 60 the cores be formed with integral extensions, instead of detachable extensions 31^a, hence the provision of the detachable extensions 31^a. The top of the mold is also provided with enlargements 33 conforming to the 65 shape of the shock absorbing blocks, when

the top is arranged in place, and the molten glass poured into the mold, with the wire fabric in sufficient quantities to hold the glass in place, the glass allowed to cool and be tempered, the enlargements 33 will form 70 the depressions 4. Obviously when the top of the mold is removed and the body of the mold likewise removed, a suitable glass cross tie or sleeper may be constructed, the openings or passages 7 having been formed by 75 the cores 32. The sheet metal mold or shell may be bent, rolled or otherwise constructed in shape, and corrugated as shown, in order to form the outer surfaces of the tie so that the sides of the mold are corrugated longitudinally. The sides and ends of the mold or shell are capable of being bent to open 80 positions, in order to extract the tie from the shell. The sides and ends may be moved far enough so that the tie will pass the 85 lower parts of the corrugations of the sides of the shell, when the shell is inverted, to discharge the cross tie.

When molding a cross tie of glass, the mold is placed in position, the sides and 90 ends arranged as shown, after which the sheet metal reinforcing with its reinforcing sleeves or tubes, together with the wire fabric reinforcing are supported in any suitable manner (not shown), in order to be 95 incased or embedded in the glass tie. The molten glass, heated to a very high temperature, is then poured through the openings 28^a of the top, the same flowing into the mold around the sheet metal reinforcing, 100 through the openings 43 and through the openings of the wire mesh or screen, thereby incasing or embedding such reinforcing parts in the glass. The tie is allowed to set, cool, and may be properly tempered and 105 treated according to known science, and is then ready for use for forming a sleeper for the rails of a railroad. A sleeper or tie of this character is particularly adapted as an insulator of electricity. In order to remove 110 a rail, or to remove a tie, the nuts 17 may be detached, by first removing the cotter pins, lifting the plates 14 from the anchors, then the tie may be slid from under the rail, the rail being partly jacked up. If desired 115 a wrench may be applied to the heads 13, turning the anchors, so that the lugs 10 may assume positions, which they first assumed when inserting the anchors, after which the anchors may be extracted. Or the nuts 17 120 may be loosened, and the plates 14 turned, which will allow the rails to be lifted. The sheet metal reinforcing trough is corrugated, in other words constructed to conform to the shape of the mold, though it is obvious that 125 the sheet metal reinforcing, and also the mold may be otherwise shaped. The amount of elasticity and rigidity of a tie of this character has been found very essential and practical for use on railways. Furthermore 130

the glass is not subjected to rust, or indentation of the rock ballast, which is otherwise caused in case the tie is constructed of fibre or wood, for the reason that the rock of the 5 road bed acts to cut into the fibre or wood, and destroys the strength thereof. It will be noted that a bolt or rod 34 passes through one of the reinforcing sleeves 2, as shown in Figure 6, and provided with a nut, as shown, 10 to not only assist in supporting the sheet metal reinforcing in place, but also to hold and reinforce the sides of the mold. It is obvious that more or less of such bolts may be used through others of the sleeves 2, 15 though it is not absolutely necessary.

In making the extensions 31^a in a plurality of parts, as may be found necessary the sections or parts may be joined by joints similar to 31. The wire fabric which is 20 bedded in the tie is so arranged as not to come in contact with the metal fastenings for the rails, thereby avoiding short circuiting the current in electrical block signal systems, thereby in this way providing an insulator. The glass acts to preserve the metal parts (which are encased in the tie) against 25 rust, and also obviates wear caused through vibration. In other words should the metal be exposed to the weather, the corrosion of 30 the metal, particularly the sheet metal reinforcing, would tend to eat holes in the reinforcing, which would eventually lessen the strength and durability of the tie. A tie of 35 the present character, wherein a glass body is used is of a non-decaying type, as well as being fire-proof.

The invention having been set forth, what is claimed as being useful is:

1. In a device of the character and for the 40 purpose indicated, the combination with a glass tie body having wire fabric reinforcing, the greater portion of which being located near the bottom of the tie body, said tie body having openings or passages located 45 adjacent the rail engaging parts of the tie, for the reception of rail anchors.

2. In a device of the character and for the 50 purpose indicated, the combination with a glass tie body having wire fabric reinforcing, the greater portion of which being located near the bottom of the tie body, said tie body having openings or passages located adjacent the rail engaging parts of the tie, for the reception of rail anchors, said tie 55 body having transversely disposed sleeves, which act to reinforce the glass tie body, and at the same time constituting means to prevent the pulling in of the sides of a mold or shell, during the construction of the body.

60 3. In a device of the character and for the purpose indicated, the combination with a glass tie body having wire fabric reinforcing, the greater portion of which being located near the bottom of the tie body, said tie 65 body having openings or passages located

adjacent the rail engaging parts of the tie, for the reception of rail anchors, said tie body having depressions suitably spaced according to the spacing of rails, the walls of the depressions being V-shaped, and shock 70 absorbing blocks correspondingly formed and engaged in said depressions.

4. In a device of the character for the purpose indicated, a glass tie body provided with wire fabric reinforcing therein, said tie body having depressions on its upper surface adjacent the ends of the tie body, shock absorbing members treated with creosote corresponding to and engaged in said depressions, said tie body having openings 75 adjacent said depressions, rail anchors mounted in said openings and being operatively connected to rails which are adapted to be mounted on the shock absorbing members, means for connecting the lower ends of 80 the anchors in said openings, said anchors having grooves, and elements frictionally engaged in the openings and engaged with the grooves of the anchors, for forcing the anchors into position and preventing disengagement of the anchor securing means. 90

5. In a device of the character and for the purpose indicated, a glass tie body, a reinforcing therein, the upper surface of the tie adjacent its ends being provided with 95 depressions, said depressions having V-shaped opposite walls, shock absorbing members engaging said depressions, the walls of the depressions and the corresponding walls of the blocks constituting means to prevent 100 lateral movement of the blocks, whereas the weight of the rail resting thereupon retains the rails in said depressions.

6. In a device of the character and for the purpose indicated, a glass tie body provided on its upper surface at spaced rail 105 positions with shock absorbing blocks, said body having vertical openings or passages, anchors engaging said passages and provided with locking means at their lower ends to 110 assist in holding the anchors in place, plates engaged with the anchors and overlying the rails which seat upon the shock absorbing members, keys mounted in said passages or openings and engaging the anchors to hold 115 them in position, said plates overlying the keys to prevent upward movement of the rails for retaining the plates on the anchors.

7. In a device of the character and for the purpose indicated, a glass tie body having 120 seats for spaced rails, openings extending vertically through the body diagonally on opposite sides of each rail, plate anchors engaging said openings and being interlocked 125 in engagement with the lower ends of the openings, plates on said anchors overlying the rails, said anchors having grooves, keys in said openings and engaging said grooves to wedge the anchors to one side of the open- 130

ings, and means for retaining the plates on the anchors.

8. The combination with a tie having rail seats and provided with openings, anchors in the openings and having grooves, means conforming to and engaging the openings and the grooves of the anchors, for holding the anchors in one side of the openings, rail retaining plates on the anchors, and means carried by the anchors for holding the plates in position.

9. The combination with a tie body having rail seats and provided with openings on opposite sides of the rail, rail plate anchoring members connected to the lower ends of said openings, wedge keys in said openings and engaged with the anchors to prevent them from turning and to wedge them to corresponding sides of the openings, and rail plates retained on the anchors for holding the rails in position, said wedge keys having enlargements at their upper ends, so as to be engaged by the hand of the mechanic, for extracting the wedge keys from the openings, the upper ends of the anchors having rectangular heads, to be engaged by a wrench, for rotating the anchors.

10. In a device of the character and for the purpose indicated, a mold, a sleeve engaged between the sides of the mold, means passing through the sides of the mold and through the sleeve, to rigidly reinforce the sides of the mold, the top of the mold having cores for forming depressions in the top of a glass tie being constructed by the mold.

11. In a device of the character and for the purpose indicated, a mold, a sleeve engaged between the sides of the mold, means passing through the sides of the mold and through the sleeve, to rigidly reinforce the sides of the mold, the top of the mold having cores for forming depressions in the top of a glass tie being constructed by the mold, the top of the mold having cores for forming openings in a tie, to be constructed by the mold.

12. In a device of the character and for the purpose indicated, the combination with a glass tie body having wire fabric reinforcing, the greater portion of which being located near the bottom of the tie body, a sheet metal reinforcing embedded in said body, and means for attaching rail anchors to the tie for holding the rails in position.

13. In a device of the character and for the purpose indicated, the combination with a glass tie body having wire fabric reinforcing, the greater portion of which being located near the bottom of the tie body, a sheet metal reinforcing embedded in said body, and means for attaching rail anchors to the tie for holding the rails in position, said sheet metal reinforcing having a plurality of openings, through which the molten

material flows, so as to thoroughly incase or embed the reinforcing in position.

14. In a device of the character and for the purpose indicated, the combination with a glass tie body having wire fabric reinforcing, the greater portion of which being located near the bottom of the tie body, a sheet metal reinforcing embedded in said body, and means for attaching rail anchors to the tie for holding the rails in position, said sheet metal reinforcing having a plurality of openings, through which the molten material flows, so as to thoroughly incase or embed the reinforcing in position, and means extending transversely of the tie body and connecting opposite portions of the sheet metal reinforcing, to hold the parts in position and strengthen the tie, and yet at the same time permit of elasticity.

15. In a device of the character and for the purpose indicated, the combination with a glass tie body having wire fabric reinforcing, a sheet metal reinforcing embedded in said tie body and having openings in opposite parts of the sheet metal reinforcing, to permit of the flow of molten glass about the sheet metal reinforcing, in order to form the tie.

16. In a device of the character and for the purpose indicated, the combination with a glass tie body having wire fabric reinforcing, a sheet metal reinforcing embedded in said tie body and having openings in opposite parts of the sheet metal reinforcing to permit of the flow of molten glass about the sheet metal reinforcing, in order to form the tie, and means connecting the opposite sides of the sheet metal reinforcing to hold the sides in position, and to strengthen the tie as well as insuring elasticity.

17. In a device of the character and for the purpose indicated, the combination with a glass tie body having wire fabric reinforcing, a sheet metal reinforcing embedded in said tie body and having openings in opposite parts of the sheet metal reinforcing, to permit of the flow of molten glass about the sheet metal reinforcing, in order to form the tie, and means connecting the opposite sides of the sheet metal reinforcing to hold the sides in position, and to strengthen the tie as well as insuring elasticity, and means for permitting the attachment of rail anchors to the tie for holding the rails in position.

18. In a device of the character and for the purpose indicated, a mold, a sleeve engaged between the sides of the mold, means passing through the sides of the mold and through the sleeve, to rigidly reinforce the sides of the mold, the top of the mold having cores for forming depressions in the top of a glass tie being constructed by the mold, and means connecting the opposite sides of the mold and passing through the tie, to assist

in supporting the reinforcing parts of the tie in position while being formed.

19. In a device of the character and for the purpose indicated, the combination with a 5 glass tie body having a sheet metal reinforcing, tubular members connecting the opposite parts of the sheet metal reinforcing to hold the same in shape while the tie body is being molded, one of said tubular members 10 adapted to receive a supporting member of a mold, to support the reinforcing in position, while the tie body is being molded.

20. In a device of the character and for the purpose indicated, the combination with 15 a glass tie body having a sheet metal rein-

forcing, tubular members connecting the opposite parts of the sheet metal reinforcing to hold the same in shape while the tie body is being molded, one of said tubular members adapted to receive a supporting member of 20 a mold, to support the reinforcing in position, while the tie body is being molded, said sheet metal reinforcing having openings to permit of the flow of molten material, when embedding the reinforcing in the tie 25 body.

In testimony whereof I hereunto affix my signature.

PATRICK J. DUNN.
